ALBERT JAMES COOPER, OF KEW, AND ALWYN ALFRED HOPE BILNEY, OF LONDON,
ENGLAND.

HINGED JOINT.

Application filed November 2, 1926, Serial No. 145,874, and in Great Britain December 10, 1925.

This invention is for improvements in or relating to hinged joints, and has for one of its objects to cheapen the cost of manufacture of hinged joints, and for another object 55 to facilitate the assembly of the members of hinged joints. The invention is particularly adapted for embodiment in tin boxes, but it is also capable of other applications.

According to the primary feature of the 10 present invention there is provided a hinged joint having a hinge pivot carried by (for example integral with) one member of the joint, and a bridge-like housing so placed on (for example pressed out of the material of) 15 the other member of the joint as to receive the pivot, which hinged joint is characterized in that the material adjacent to the housing is slit in such a manner that a slit or slits extend to an edge of the material of 20 the hinge member, so that the parts of the hinge member on each side of the slit are movable relatively to each other, to permit the passage of the hinge pivot into or out of the said housing, which parts, however, are 25 normally in position to obstruct the said passage of the hinge pivot. This arrangement will be found to promote ease of assembly of the members of the joint and consequently to cheapen the cost of production.

According to another feature of the present invention a hinged joint as aforesaid and having two bridge-like housings which receive both ends of the pivot is provided which is characterized in that the material 35 adjacent to each housing is left unslit through at least one half of the outline of the respective housings (for example is left unslit on at least two adjacent sides of a rectangle bounding a housing). In this way 40 the strength of the hinge members will be retained without interfering with the ease of assembly of the members.

According to a further feature of the invention, the material adjacent to one only of 45 said housings is slit in such a manner to allow that housing to move so that the hinge pivot may be placed in operative position. Thus, since only one end of the housing-carrying member is slit, 50 such member will be stiffer than if it were slit at more places, and furthermore the assembly of the members of the joint is facilitated.

According to another feature of the in-

vention, the material adjacent to one or more 55 housings is provided with a slit whereof the disposition and formation are so correlated with the stiffness of the material that the housing or housings can be forcibly displaced to allow the hinge pivot to assume its 60 operative setting, and will afterwards automatically spring back into position to retain the pivot in such operative setting. By adopting such an arrangement, it becomes 65 unnecessary to return the housings to their operative position by manual or other operation, thus simplifying the procedure in assembling the hinge members.

Conveniently to a housing there is only 70 one slit extending to an edge of the material of the hinge member. Each housing may have one open and one blind end and it is preferred that the slit shall be located solely at the open end of the housing. The slit will usually lie at right angles to the axis 75 of the hinge pivot.

For a more complete understanding of the invention there will be now described, by way of example only and with reference to the 80 accompanying drawings, certain constructional forms of hinged joints according to the invention. It is to be understood, however, that the invention is not restricted to the precise constructional details set forth.

In these drawings:—

Figure 1 is a composite perspective view 85 of the lid and body of a tin box constructed according to the present invention and showing them detached one from the other.

Figure 2 is a perspective view corresponding 90 to Figure 1, but showing the two parts of the box assembled.

Figure 3 is a composite perspective view 95 showing the two parts of a hinge constructed according to the present invention and intended to be secured to the two parts which it is required to hinge together. The details of construction illustrated in Figure 3 differ somewhat from those shown in Figures 1 and 2.

Like reference numerals indicate like parts 100 throughout the drawings.

Referring firstly to Figures 1 and 2, it will be seen that the rear wall 10 of the rim on the lid 11 has an inverted T-shaped extension 12 lying more or less in the same plane as that of the wall 10. The head 13 of the T is channelled and constitutes the hinge 105

pivot, the concave face of the channel being directed towards the interior of the box when the lid is in its closed position. The rear wall 14 of the body 15 of the box is formed with two bridge-like housings 16 and 17, each with one open and one blind end whereof the open ends are directed towards each other. The material 18 of the wall 14 between the housings is offset inwardly in order to permit the hinge pivot to work freely, and a single slit 19 is provided which is at right angles to the axis of the hinge pivot and is adjacent to the mouth of the housing 17, it extending from the top edge of the wall 14 to the entrance of the housing.

To assemble the two parts of the box, the appropriate hinge pivot end is inserted in the housing 16 and pressure is applied to open the slit 19 which will allow the other hinge pivot end to be inserted and forced downwards into the housing 17. As the hinge pivot ends now rest on the housings provided for them, the material of the side of the box which was temporarily displaced during this latter operation will spring back to its normal position and retain the hinge pivot in its operative setting.

The operations in the construction of the members of the hinged joint can be carried out either singly, successively, or simultaneously, as desired; furthermore, the said operations together with the assembly of the members of the hinged joint may be carried out by hand, or hand- or power-operated mechanism as required.

The construction shown in Figure 3 comprises a pair of plates 20 and 21 which are intended to be attached by screws or other fastenings to two members which are required to be hinged together. The plate 20 has two L-shaped projections 22 and 23 whereof the bases form the hinge pivot of the joint, these bases being in alignment and being channelled with their concave faces directed in the opposite direction to that in which the concave face of the hinge pivot shown in Figures 1 and 2 is directed. In some circumstances the arrangement shown in Figure 3 is preferable since a rounded portion of the hinge pivot will bear against the co-operating member of the joint. The plate 21 has two housings 24 and 25 which are similar in construction to those shown in

Figures 1 and 2, but are reversed in setting so that their open ends are directed away from each other. These is a single slit 26 adjacent to the mouth of the housing 25.

To assemble the parts shown in Figure 3, the pivot 22 will first be inserted into the housing 24, after which the slit will be sprung open and the pivot 23 forced into place in its housing 25. Preferably this operation will be carried out before the plates 20 and 21 are attached to the members which they are required to hinge together.

It will be appreciated that in the various constructions described and illustrated, the material around any one housing is not slit through more than one half of the outline thereof. Consequently, adequate support is offered to the housing and moreover, it is possible to arrange the housing to spring back automatically into pivot-retaining position after the pivot has been inserted.

It is to be understood that the invention is not restricted to the precise constructional details set forth. For instance, although in each joint only one slit extending to an edge of the material of the hinge member is shown, there may in some circumstances be more than one such slit. However, the fewer of such slits the better from the point of view of the strength of the hinge members.

We claim:

A hinged joint for connecting a cover to a box without the use of tools, the cover having two oppositely extending pivots connected thereto, the box having two oppositely disposed housings extending beyond the outer face of the box, there being an opening to each of the housings, while the other ends of the housings are closed and merge into the body of the box, one of the housings being connected to the body of the box at both sides of the opening, there being a slit from the top of the box to the opening to the other housing, whereby one of the pivots can be entered into the opening of the first mentioned housing after which the second pivot can be inserted into its housing by passing it through the slit.

In testimony whereof we have signed our names to this specification.

ALBERT JAMES COOPER.

ALWYN ALFRED HOPE BILNEY.
